CLAIM

The ornamental design for a beam splitting adjustable c-mount optical coupler, as shown and described.

DESCRIPTION

FIG. 1 is a right side elevational view of a beam splitting adjustable C-mount optical coupler, showing my new design;

FIG. 2 is a left side elevational view thereof;

FIG. 3 is a front elevational view thereof;

FIG. 4 is a rear elevational view thereof;

FIG. 5 is a top plan view thereof;

FIG. 6 is a bottom plan view thereof.
